UNITED STATES PATENT OFFICE.

BENJAMIN G. TAITE, OF PHILADELPHIA, PENNSYLVANIA.

DESIGN FOR AN ORNAMENTAL TOILET-POWDER BOX.

SPECIFICATION forming part of Design No. 29,259, dated August 23, 1898.

Application filed July 16, 1898. Serial No. 686,154. Term of patent 14 years.

To all whom it may concern:

Be it known that I, BENJAMIN G. TAITE, a citizen of the United States, residing in the city of Philadelphia, State of Pennsylvania, have invented and produced a certain new and original Design for Ornamental Toilet-Powder Boxes and Like Articles, of which the following is a full, clear, and exact description, reference being had to the accompanying drawings, forming a part of this specification.

My invention relates to the external surface ornamentation of small sheet-metal boxes usually employed in putting up face-powders, tooth-powders, and other pulverized toilet preparations; and my invention consists of the design therefor shown in the accompanying drawings, in which—

Figure 1 is a view showing a box in dotted-line perspective and in full lines a development in plan or diagram of the body of the box and the vertical rim of the lid. Fig. 2 is an end view of the box with its lid.

The design I have invented consists, for the

body of the box, of an oval frame-like figure *a* with torches on each side for one side and *b* a more or less rectangular frame-like figure *b* for the opposite side of the box, the remaining space being filled in with a series of crowns *c*, surrounded by wreaths. The lid has an exterior ring of bead figures *e*, inclosing a *f* wreath, and the latter inclosing a large crown-figure *g*, the vertical rim of the lid (see Fig. 1) having impressed thereon a series of crown-figures *d*.

I claim as my invention—

The design for an ornamental toilet-powder box or like article, substantially as shown and described.

In testimony whereof I have hereunto affixed my signature this 15th day of July, A. D. 1898.

BENJAMIN G. TAITE.
